MICHAEL RIESNER, OF CINCINNATI, OHIO, ASSIGNOR TO WORTHINGTON PUMP AND MACHINERY CORPORATION, OF NEW YORK, N. Y., A CORPORATION OF VIRGINIA.

VARIABLE-CAPACITY COMPRESSOR.

Application filed November 10, 1926. Serial No. 147,540.

This invention relates to air or gas compressors and more particularly to means for automatically unloading the compressor, in a graduated manner, when the receiver pressure rises to pre-determined degrees and loading it in a graduated manner as the receiver pressure falls, and the primary object of the invention is to provide an apparatus of this type which will be economical in operation, provide for a relatively high efficiency compressor and one which will be relatively simple in construction and consequently, cheaper to manufacture than those heretofore used, and especially suitable for compressors of constant speed.

The present invention contemplates the use in a variable capacity compressor, of clearance chambers and by-pass which opens into the suction port of the compressor, thereby preventing excessive heating when the compressor is running or operating at zero capacity, together with suitable pressure operated control apparatus to permit the graduated unloading and loading of the compressor cylinder, for permitting its operation under various pre-determined percentages of its full capacity.

For a full understanding of the invention, a detailed description of constructions embodying the same in preferred form will now be given in connection with the accompanying drawings forming a part of this specification, and the features forming the invention then specifically pointed out in the claims.

In the drawings—

Figure 1 is a diagrammatic section of the variable capacity compressor constructed in accordance with this invention.

Figure 2 is a cross section through the compressor taken on the line 2—2 of Figure 1.

Figure 3 is a section through a modified form of the compressor.

Figure 4 is a cross section through the modified form of the compressor taken on the line 4—4 of Figure 3.

Referring more particularly to the drawings, the improved compressor comprises a cylinder 1 having a head end 2, a crank end 3 with the usual type of piston 4 mounted for reciprocatory movement within the cylinder for the compression of the air or gas.

In the construction illustrated in Figure

1 of the drawings, clearance chambers 10 and 11 are provided which are of unequal capacity, the clearance chamber 11 having a greater capacity than the clearance chamber 10. However, this arrangement may be reversed without departing from the spirit of the invention. A port 12 establishes communication between the crank end 3 of the cylinder 1 and the clearance chamber 10, and this port is closed by valve 13. A port 14, which is controlled by the valve 15 establishes communication between the head end 2 of the cylinder 1 and the clearance chamber 11. The clearance chambers 10 and 11 have communication through ports 16 and 17 respectively with the by-pass 18 which extends to and has communication with the suction port or intake 18' of the air compressor.

The valve 13 is actuated by a pressure operated piston 19 which is moved in its cylinder 20 by receiver pressure while the valve 15 which controls the port 14, and the valve 21 which controls the ports 16 and 17 are actuated by pressure operated pistons 22 and 23 respectively.

Operation of the pistons 19, 22 and 23 is automatically controlled by a control apparatus of approved construction, such as the control apparatus illustrated and described in my co-pending application, Serial #136,008 and prior Patents #1,579,781 and #1,579,782, the pistons being operated to close the valves by low pressure fluid admitted through pipes 28 and 30 from the intermediate receiver or other suitable supply.

The clearance chambers 10 and 11 may be of any desired capacity so as to unload and load the cylinder 1 in the steps required, but assuming that the capacity of the clearance chamber 10 is such as to unload one-half of the crank end 3 of the compressor, while the capacity of the clearance chamber 11 is such as to completely unload the head end of the cylinder, the operation of the construction shown and above described is as follows: Assuming that the compressor is operating at full capacity, an increase in receiver pressure above that for which the apparatus is set will operate the piston 19 through the control apparatus (not shown), admitting fluid under pressure to the inside of the piston through the pipe 24 and port

25 and move the piston outwardly, unseating the valve 13 and opening the crank end of the cylinder 1 to the clearance pocket 10. The compressor will then operate at 75% capacity.

On a further increase of receiver pressure the piston 22 will be moved outwardly by fluid under pressure admitted through the pipe 26 and port 27 for unseating the valve 15, which will open the head end 2 of the cylinder to the clearance chamber 11, and at the same time the pressure fluid will be cut off from pipe 24 so that the lower pressure fluid from pipe 28 will seat the valve 13 and close the crank end of the cylinder from the clearance chamber 10, thus permitting a 50% unloading of the cylinder, by the clearance chamber 11 at which time the compressor will operate at 50% capacity.

20 On a still further increase of receiver pressure the fluid under pressure, admitted through the pipe 24 and port 25 will again operate the piston 19 to unseat the valve 13 which will open the crank end 3 of the cylinder 1 to the clearance pocket 10. At this time the head of the cylinder will be completely unloaded while the crank end will be one-half unloaded and the compressor will operate at 25% of its capacity.

30 Should the receiver pressure rise or increase still further, the fluid under pressure will be admitted through the pipe 29 on the inner side of the piston 23 and will move this piston outwardly, unseating the valve 21 which will open the clearance pockets 10 and 11 to the suction port of the compressor through the by-pass 18 allowing the air to move back and forth from one end of the cylinder to the other, at which time the compressor will be completely unloaded and will operate at zero capacity. The opening of the clearance pockets 10 and 11 to the suction port of the compressor will prevent such excessive heating as might be encountered due 40 to the same air being churned back and forth in the compressor, if completely unloaded by clearance pockets and by-pass only, because as constructed fresh cool air is drawn into and expelled from the cylinder on each 45 stroke.

50 Decrease in receiver pressure reverses the operation above described, the compressor being loaded in a graduated manner in the same proportions of its full capacity as those in which it is unloaded; i. e. upon decrease in receiver pressure the admission of the fluid under pressure against the inner surface of the piston 23 is relieved, through the control apparatus, such as described in 55 the above mentioned application and prior patents, and when this pressure is relieved from the inner side of the piston the relatively low pressure which is admitted to the piston through the pipe 30 will seat the 60 valve 21 cutting off communication between 65

the clearance pockets 10 and 11 and the by-pass 18, at which time the compressor will be operating at 25% capacity.

A further decrease in receiver pressure will cut off the supply of fluid under pressure 70 against the inner surface of the piston 19 and this piston will be operated through the lower pressure fluid admitted through the pipe 28 to close the valve 13 and permit the compressor to operate at 50% capacity or 75 with the head end wholly unloaded.

As the receiver pressure further decreases the pressure on the inner side of the piston 22 is cut off and the valve 15 is seated; however, at the same time that the valve 15 is seated, the pressure is again admitted to the inner side of the piston 19 so that the valve 13 is opened at the same time that the valve 15 is closed, and this permits the compressor to operate at 75% capacity, owing to the fact 80 that the crank end 3 is one-half unloaded by the clearance chamber 10.

The final step of loading of the compressor is through the closing of the valve 13 in the same manner as above described, which 90 completely cuts off the cylinder 1 from communication with the clearance chamber 10 and allows the compressor to operate at 100% capacity.

In Figure 2 of the drawings a modified construction of the compressor is shown in which clearance chambers 50 and 51 are provided which have communication with the crank end 52 and head end 53 of the cylinder 54 through the ports 55 and 56 respectively. The clearance chambers 50 and 51 have communication with a by-pass 57 through ports 58 and 59 respectively and the by-pass 57 has communication with the suction port or intake 57' of the compressor. 95

A valve 60 controlling the port 55 and a valve 61 controls the port 56. The valves 60 and 61 are actuated by pressure operated pistons 62 and 63 respectively, which move in cylinders 64 and 65. Fluid under pressure is admitted against the inner sides of the piston 62 and 63 through pipes 66 and 67 for operating the pistons to unseat the valves 60 and 61, and admittance of the fluid under pressure into the cylinders 64 and 65 against the inner sides of the pistons 62 and 63 is controlled by a control apparatus of approved construction, such as that disclosed in my co-pending application and prior patents above mentioned. 110

The ports 58 and 59 are controlled by valves 68 and 69 which are operated by pressure operated pistons 70 and 71 movable in cylinders 72 and 73. Fluid under pressure is admitted to the cylinders 72 and 73 against the inner sides of the pistons 70 and 71 through pipes 74 and 75, and such admission of fluid under pressure is controlled by the same control apparatus, which controls the admittance of fluid under pressure to 115 120 125 130 135

the cylinders 64 and 65. A low pressure fluid is admitted to each of the cylinders 64, 65, 72 and 73 against the outer sides of the pistons 62, 63, 70 and 71 for seating the valves 60, 61, 68 and 69 when the flow of fluid under pressure against the inner sides of the respective pistons is cut off.

The clearance chambers 50 and 51 may be of any desired capacity so as to unload and load the cylinder 54 in the steps required, but assuming that the capacity of each clearance chamber is such as to provide a one-third unloading of the cylinder 54, the operation of the construction shown and above described is as follows: Assuming that the compressor is operating at full capacity, an increase in receiver pressure above that for which the apparatus is set will operate the pistons 62 and 63 for opening the valves 60 and 61, which opens the crank end 52 and head end 53 of the cylinder to the clearance chambers 50 and 51, at which time the compressor will be operating at 66% capacity. Upon a further increase in receiver pressure the valve 68 will be opened by operation of the piston 70 which will by-pass the crank end 52 of the cylinder through the clearance chamber 50 and by-pass 57 to the suction port of the compressor, at which time the compressor will operate at 33% capacity.

On a still further increase in receiver pressure the valve 69 will be opened which will open the clearance chamber 51 to the by-pass 57 and thus by-pass the head end of the cylinder 54 through the clearance chamber 51 and by-pass 57 to the suction port of the cylinder, at which time the compressor will operate completely unloaded or at zero capacity.

Decrease in receiver pressure reverses the above described operation, the compressor being gradually loaded in the same proportions of its full capacity as those in which it is unloaded.

By variance of the control apparatus, the steps of unloading the compressor as just above described may be varied and instead of opening the valves 60 and 61 simultaneously to open the crank and head ends of the cylinder to the clearance pockets 50 and 51, these valves may be operated in sequence which will add an additional step to the unloading of the compressor or if desired, the control apparatus may be arranged to operate the valve 68 and 69 simultaneously in lieu of in sequence which would subtract a step in the operation of unloading and loading the compressor from the steps specifically described above, and it is to be understood that such variations may be made without departing from the spirit of this invention.

It will be understood that the invention is not to be limited to the specific construc-

tion or arrangement of parts shown but that these may be modified widely within the invention defined by the claims.

What is claimed is:

1. In a variable capacity compressor, the combination with a cylinder, of a plurality of clearance chambers, a by-pass port communicating with said clearance chambers and with the suction of the cylinder, and pressure operated means for partially unloading said cylinder by said clearance chambers and for wholly unloading the cylinder by said clearance chambers and by-pass. 75

2. In a variable capacity compressor, the combination with a cylinder, of clearance chambers, a by-pass between the ends of the cylinder and to the suction port of the cylinder, and pressure operated means for partially unloading said cylinder by said clearance chambers and wholly unloading the cylinder by opening said by-pass. 80

3. In a variable capacity compressor, the combination with a cylinder, of a clearance chamber for partially unloading the crank end of said cylinder, a by-pass port having communication with the suction of the cylinder and with said clearance chamber for wholly unloading the crank end of the cylinder. 90

4. In a variable capacity compressor, the combination with a cylinder, of a clearance chamber for partially unloading the crank end of said cylinder, a by-pass port having communication with the suction of the cylinder and with said clearance chamber for wholly unloading the crank end of the cylinder, and a second clearance chamber for unloading the head end of the cylinder, said by-pass having communication with said second clearance chamber for opening it to the suction of the cylinder for wholly unloading the cylinder. 100

5. In a variable capacity compressor, the combination with a cylinder, of a clearance chamber for partially unloading one end of the cylinder, a second clearance chamber, a by-pass port having communication with said clearance chambers and with the suction port of the compressor, and pressure operated means for opening the ends of the cylinder to said clearance chambers in sequence and for simultaneously opening said clearance chambers to said by-pass. 110

6. In a variable capacity compressor, the combination with a cylinder, of a plurality of clearance chambers, pressure operated means for partially unloading said cylinder gradually by opening of the clearance chambers to said cylinder, a by-pass having communication with the suction of the cylinder and with said clearance chambers, and pressure operated means for opening said clearance chambers to said by-pass. 125

7. In a variable capacity compressor, the combination with a cylinder, of a plurality 130

- of clearance chambers, pressure operated means for partially unloading said cylinder gradually by successive opening of the clearance chambers to said cylinder, a by-pass having communication with the suction of the cylinder and with said clearance chambers, and pressure operated means for simultaneously opening said clearance chambers to said by-pass.
10. 8. In a variable capacity compressor, the combination with a cylinder, of a plurality of clearance chambers, pressure operated means for partially unloading said cylinder gradually by opening of the clearance chambers to said cylinder, a by-pass having communication with the suction of the cylinder and with said clearance chambers, and pressure operated means for successively opening said clearance chambers to said by-pass.
15. 9. In a variable capacity compressor, the combination with a cylinder having an intake, of a clearance chamber, a by-pass having communication with said chamber and with the suction of the cylinder, a pressure operated valve for opening said chamber to the cylinder and a second pressure operated valve for opening said chamber to said by-pass.
10. In a double acting variable capacity compressor, the combination with a cylinder having an intake, of two clearance chambers, one having greater capacity than the other, a by-pass having communication with said clearance chambers and said intake, pressure operated valves for controlling connection of said clearance chambers with said cylinder and pressure operated valves for controlling connection of said chambers with said by-pass.
- In testimony whereof I affix my signature. 40
- MICHAEL RIESNER.
